Patented July 13, 1915.

FIG. 1

FIG. 2

FIG. 3

UNITED STATES PATENT OFFICE.

WILLIAM S. HADAWAY, JR., OF NEW ROCHELLE, NEW YORK.

CURLING-IRON HEATER.

1,146,758.

Specification of Letters Patent.

Patented July 13, 1915.

Application filed October 10, 1913. Serial No. 794,397.

To all whom it may concern:

Be it known that I, WILLIAM S. HADAWAY, Jr., a citizen of the United States, residing at New Rochelle, in the county of Westchester and State of New York, have invented new and useful Improvements in Curling-Iron Heaters, of which the following is a full, clear, concise, and exact description, reference being had to the accompanying drawing, forming a part of this specification.

My invention relates to curling-iron heaters of the wall type. Devices of this character, as constructed heretofore, have required the turning on of the heating current as an act separate and distinct from the insertion of the curling-iron, and as a preliminary thereto. In certain cases, the entrance of the heating chamber has been completely closed by a sliding gate which required to be slid to one side to permit the curling-iron to be inserted. The complete operation, therefore, involved the use of both hands. With one hand the gate was slid to open position, and with the other hand the curling-iron was inserted.

One of the objects of my invention is to provide an improved construction whereby only one hand is required to insert the curling-iron in the heating chamber, the said insertion being accompanied necessarily and automatically by the closing of the heating circuit, the latter being likewise opened by the withdrawal of said curling-iron.

Another object is to provide a curling iron heater having improved means for securing ventilation thereof.

Another object is to provide a curling iron heater which may be readily assembled and installed.

Another object is to provide a curling iron heater in which the parts thereof are readily accessible.

Another object is to provide a curling iron heater of increased simplicity and durability.

Other objects and advantages of the invention will hereinafter appear.

The accompanying drawings illustrate an embodiment of the invention.

Figure 1 is a front elevation of the cover plate. Fig. 2 is a front elevation of the outlet box with all the parts removed therefrom which ordinarily obstruct the open end thereof. Fig. 3 is a front elevation of the

device with the cover plate removed. Fig. 4 is a central sectional elevation thereof.

The structure, in its preferred form, comprises, generally speaking, an outlet box 1 set into a wall, being embedded usually in the plaster, and a supporting plate 2, which carries all the remaining parts of the device and which is secured to the front of the outlet box and covers the open end thereof. The outlet box, which is made preferably of sheet metal, need not necessarily constitute part of the equipment as manufactured, but may be installed at the time the room is plastered, for example. The curling-iron heater proper may thereafter be installed simply by securing it in position. For this purpose, the front of the outlet box is preferably flanged inwardly as at 3, said flanges each having a screw-threaded hole 4 therein, as shown. The supporting plate 2, which is made preferably of cast iron, is held to said flanges by screws 5 passing through elongated openings 6 therein, the latter permitting a slight adjustment of said plate, if necessary. The outlet box may be provided further with a suitable opening or openings 7 to permit the introduction of conductors from the usual conduit located in the wall.

A heating tube 8 is fitted within a suitable opening in the supporting plate 2, said heating tube having a suitable resistance wire 9 wound about the same and insulated therefrom by insulation 10 of any approved kind. Said heating tube is open at both ends and is secured at its forward end to the outer face of the supporting plate by screws 11, 12. The screws 12 also securely hold in place one end of a resilient member 13, which is preferably a strip of metal, said strip being arranged somewhat diagonally with respect to the main axis of the tube, and extending through the rear end thereof. A suitable bridging member 14 is carried by the rear end of said strip, which latter is preferably bent up above the heating tube, whereby said bridging member may close the circuit between a pair of resilient contact members 15. Said bridging member is preferably insulated from said resilient strip, being secured thereto by metal pins or rivets 16, but spaced therefrom by suitable layers of mica 17, arranged on both sides thereof, as shown. The contact members 15 are each secured in any suitable manner to a metal bracket 18, the latter being secured to the wall 19 of a

shallow recess in the supporting plate 2. The rear ends of said bracket 18 constitute stops for the resilient contacts 15, said contacts being lifted somewhat by the bridging member 14 when the circuit is closed by the upward movement of the latter. The insertion of the curling-iron forces the resilient strip 13 to one side, thereby moving the bridging member 14 to circuit-closing position, the various parts being moved about as indicated in dotted lines in Fig. 4.

The brackets 18 are secured in place by suitable screws 20, 21, as shown. An additional screw 22 passes through the wall 19, previously mentioned, the screws 20 and 22 constituting binding posts or terminal connectors for the conductors which enter the outlet box and which are brought forward through an opening 23 in said wall 19. One of said terminal screws is electrically connected to one end of the resistance wire 9 and the other terminal screw is electrically connected to the resilient contacts 15, the other of said contacts being connected to the remaining end of said resistance wire, whereby the bridging of said contacts 15 by the bridging member 14 closes the heating circuit.

The supporting plate 2 is provided with a marginal flange 24 having a pair of lugs 30 provided with screw-threaded openings 25 therein to receive the screws 27 which hold the cover plate 28 in position against the front of said supporting plate. The cover plate is of ornamental appearance and is provided with a suitable beveled edge, as shown in Figs. 1 and 4. It has also an opening 29 therethrough in alignment with the heating tube. The supporting plate 2 overlies the wall somewhat, as shown in Fig. 4, and being of substantial thickness, the cover plate is not flush with the face of said wall. However, it only projects a comparatively short distance therefrom so that the appearance of the device as a whole is very unobtrusive. The thickness of said plate is due to said flange 24, the provision of which permits the cover plate to be spaced some little distance from the supporting plate, whereby a suitable air space is provided. Openings 30 are preferably provided in said flange, both at the top and bottom thereof, whereof a circulation of air through said clearance space is promoted. The heating chamber being open at both ends, the heated air therein finds its way both into said clearance space and into the upper part of said outlet box, the latter communicating through the hole 23 with said clearance space so that the necessary ventilation is provided to prevent the device from becoming excessively hot. With this arrangement, additional safety is insured.

It will be noted that the only manual operation necessary is the insertion of the

curling-iron, which insertion results in closing the heating circuit. Furthermore, the withdrawal of the curling-iron opens the heating circuit, whereby waste of current is prevented. Only one hand is required for either operation. After the curling-iron has been thrust into the heating chamber, it is frictionally held in position by the pressure of the resilient strip 13 thereon. A further advantage of the arrangement described is that no elaborate manipulation of any of the parts of the device is required, such as might render difficult the use of the device by persons not familiar therewith. Also the absence of projecting switch-actuating knobs or levers not only greatly improves the appearance of the device, but renders it less liable to be deranged by careless users.

It will be understood, of course, that the above described embodiment of the invention represents only the preferred form thereof, said invention being susceptible of embodiment in various other forms. Accordingly, I do not desire to limit myself to the structural details and relative arrangement of parts described and illustrated, but desire to cover in the appended claims whatever suitable equivalent means may be devised which fall within the scope of said claims.

What I claim as new and desire to secure by Letters Patent of the United States is:

1. In a curling-iron heater, a heating tube, a resilient strip of metal secured at the front end thereof and extending inwardly diagonally across the bore of said tube, whereby the insertion of the curling-iron forces said strip to a position more nearly parallel with said bore, and circuit closing contacts actuated by the movement of said strip to close the heating circuit.

2. A curling-iron heater comprising a supporting plate having an opening therein, a heating tube supported at its forward end in said opening, a resilient metal strip extending through said tube somewhat diagonally and secured at its forward end adjacent to said opening, a contact bridging member at the rear end of said strip, and a pair of contacts carried by said plate and adapted to be bridged by said member.

3. In combination, an outlet box having an open end, a supporting plate closing said end, a heating tube open at both ends and projecting rearwardly from an opening in said plate into said outlet box, a cover plate secured to the forward side of said supporting plate and spaced therefrom, said cover plate having an opening therein above said heating tube to facilitate circulation of air through said outlet box and having marginal openings where it joins said cover plate to provide ventilation therefor.

4. In a device of the class described, a supporting plate having a shallow recessed

portion, an opening for a heating tube and a marginal flange, circuit terminals located within said recess, a heating tube fitting within said opening, and a cover plate fitting over said flange.

5. A curling iron heater having a heating chamber, a resilient strip of metal mounted adjacent one end of the chamber and extending diagonally into said chamber so that it
10 is adapted to be moved by the insertion of a curling iron, said strip having an elec-

trical contact mounted thereon coöoperating with other electrical contacts on the outside of said chamber to complete a circuit upon the insertion of a curling iron.

15

In witness whereof, I have hereunto subscribed my name in the presence of two witnesses.

WILLIAM S. HADAWAY, JR.

Correction in Letters Patent No. 1,146,758.

It is hereby certified that in Letters Patent No. 1,146,758, granted July 13, 1915, upon the application of William S. Hadaway, Jr., of New Rochelle, New York, for an improvement in "Curling-Iron Heaters," an error appears in the printed specification requiring correction as follows: Page 2, line 53, for the word "whereof" read *whereby*; and that the said Letters Patent should be read with this correction therein that the same may conform to the record of the case in the Patent Office.

Signed and sealed this 10th day of August, A. D., 1915.

[SEAL.]

R. F. WHITEHEAD,

Acting Commissioner of Patents.
